UNITED STATES PATENT OFFICE.

PLINY F. HODGES, OF ST. PAUL, MINNESOTA.

MOWING-MACHINE.

SPECIFICATION forming part of Letters Patent No. 554,601, dated February 11, 1896.

Application filed October 28, 1895. Serial No. 567,075. (No model.)

To all whom it may concern:

Be it known that I, PLINY F. HODGES, a citizen of the United States, residing at St. Paul, in the county of Ramsey and State of Minnesota, have invented certain new and useful Improvements in Mowing-Machines; and I do hereby declare the following to be a full, clear, and exact description of the invention, such as will enable others skilled in the art to which it appertains to make and use the same.

My invention relates to mowing-machines.

A floating finger-bar adapted both to rock and to fold is conceded to be essential to a good mowing-machine. Heretofore in the standard machines now in general use these motions have usually been obtained by means of a construction involving a main frame pivoted to the truck-axle, a supplemental frame pivoted to the main frame, a tongue fixed to the main frame, and a finger-bar attached to the supplemental frame by means of two pivots at right angles to each other. This construction permitted the rocking and folding motions of the finger-bar; and in order to permit the necessary play for the proper action of the pitman under the rocking or angular motion of the finger-bar the pitman was connected to the crank-pin at its outer end and to the knife-head at its inner end by means of ball-and-socket or other loose joints. This old or standard construction is objectionable in two respects, to wit: First, in extra hard cutting or upon the finger-bar meeting an obstruction there is a tendency of the draft to lift the truck-wheel from the ground and diminish or reduce the traction of the truck-wheels at the very time when traction is most needed to drive the knife, and, second, the rocking or tilting of the finger-bar changes the relative angle of the pitman-pivots at the opposite ends of the same, with the result of increasing the friction from the knife and its driving mechanism, thereby adding to the draft and more rapidly wearing out the cutting apparatus.

The object of my invention is to overcome and remove the above defects or limitations, and at the same time to reduce the cost of construction, while preserving the folding and tilting movements of the finger-bar intact.

To this end my invention consists of the

novel devices and combinations of devices hereinafter described and defined in the claims.

55

My improved mower is illustrated in the accompanying drawings, wherein, like letters referring to like parts throughout the several views—

Figure 1 is a plan view of the machine with some parts broken away. Fig. 2 is a view chiefly in right side elevation, but partly in section, on the lines $x' x'$ and $x^2 x^2$ of Fig. 1, looking inward. Fig. 3 is a front elevation of the machine with some parts broken away. Fig. 4 is a section on the line $x^3 x^3$ of Fig. 1, looking toward the front, with the truck-wheel positions indicated in dotted lines. Fig. 5 is a view similar to Fig. 2, but with the coupling cross-tree or knuckle-joint between the tongue and the truck-frame raised to its highest point and the finger-bar partly folded. Fig. 6 is a detail showing the coupling-cross-tree casting detached in plan view; and Fig. 7 is a detail, in perspective, showing one of the lugs detached which are used to connect the coupling cross-tree with the forward arms of the truck-frame.

The truck or cart wheels a are loose on the axle a' and have driving connections therewith through the ordinary pawl-and-ratchet devices, the pawl-bearing disks of which only are shown at a^2 .

The truck-frame is composed of a main or rear section b , which is sleeved or pivoted on the truck-axle a' , and a pair of forwardly-extended arms b' rigid with the section b at their rear ends and provided at their forward ends with split or divided bearing-lugs b^2 for pivotally connecting the truck-frame to a coupling cross-tree c . The yoke or bearing parts of the split lugs b^2 embrace the cross-tree c , between suitable collars c' formed thereon, and the rearwardly-projecting ends of the said lugs b^2 embrace the forward ends of the frame-arms b' and are rigidly secured thereto and to each other by bolts b^3 .

On the truck-axle a' , outward of the frame-section b , is loosely mounted a shiftable sprocket-wheel a^3 , which is subject to the action of a shipper-fork lever a^4 , working through a cam-slot a^5 in the frame-section b , as best shown in Fig. 1. The hub of the sprocket a^3 is provided with a half-clutch a^6

on its outer face, which co-operates with a half-clutch a^7 on the hub of the outer pawl-disk a^2 . By the shipper-lever a^4 the sprocket a^3 may be thrown in or out of gear with the 5 driving connections to the truck-wheels at will.

A sprocket-chain a^8 (indicated in dotted lines only in Figs. 2 and 5) connects the driving-sprocket a^3 with a small sprocket a^9 , 10 formed on the hub of a beveled-face multiplying-gear a^{10} . The gear a^{10} engages a beveled pinion a^{11} on the crank-shaft a^{12} . The crank-pin connects by pitman a^{13} to the head of the knife a^{14} for imparting the usual reciprocating motion thereto. The chain a^8 is 15 subject to the action of an automatic belt-tightener a^{15} .

The bearing c^2 for the crank-shaft a^{12} is formed on the outer end of the cross-tree c . 20 The bearing for the small sprocket a^9 and the multiplying-gear a^{10} is afforded by a stud-shaft c^4 , which extends through a housing c^3 , formed on the cross-tree c , and into the open outer end of the shaft-like portion of the said 25 cross-tree c . When thus seated, the stud-shaft c^4 is pinned fast to the housing c^3 . The housing c^3 is of the proper shape and size to inclose the lower parts of the knife-driving mechanism a^9 a^{10} a^{11} , and serves to protect 30 the same from dust and dirt.

The cross-tree c has formed integral therewith, as shown, at its inner end, a pair of horns or depending angular projections c^5 , which together constitute the finger-bar bridge.

35 The finger-bar f is secured to the shoes in the customary way, and the inside shoe f' is pivoted to the bridge by the horizontal pivots f^2 connecting the same with the horns or arms c^5 of the cross-tree c . A bearing-plate 40 f^3 is fixed to the finger-bar, and is of such shape as to form a seat for the knife-bar, where it passes over the part of the finger-bar fixed to the inside shoe f' , as best shown in Fig. 2. This bearing-plate f^3 is extended forward over the finger portion of the shoe, and 45 serves instead of a ledger-plate at that point. The bearing-plate f^3 being readily removable enables a new plate to be substituted, whenever required, under the wear and tear from 50 the knife. The upper or hook-shaped guide f^4 for the knife-head is fixed to the finger-bar in the usual way.

55 A guard-rod f^5 connects the forward end of the housing c^3 with the forward member of the bridge-pivots f^2 , and serves to protect or guard the pitman a^{13} from obstructions.

The draft-tongue g connects centrally with the cross-tree c by means of a divided or split lug g' , which embraces the cross-tree between 60 suitable collars c^6 thereon. The divided members of the said split lug g' are bolted together and through the tongue by nutted bolts g^2 , suitably applied thereto.

The draft-tongue g also connects with the 65 cross-tree c by means of a brace-rod g^3 , made fast at its forward end to the tongue, and pro-

vided at its rear end with an eye, which engages over a reduced part c^7 at the inner end of the cross-tree, and is held in place thereon by a split pin, or in any other suitable way. 70 The tongue lug or casting g' and the brace-bar g^3 , as described, serve to pivotally connect the draft-tongue g to the cross-tree c , with the effect of a long bearing for the tongue. The tongue is provided with the usual double-tree or draft appliance g^4 for the attachment 75 of the horses or draft-animals.

With the construction so far described, it must be obvious that the cross-tree c serves to couple the tongue and the cutting mechanism to the forward end of the truck-frame, with freedom for the independent pivotal movements of all of the said coupled parts. 80

Otherwise stated, the finger-bar bridge and the bearings for the knife-driving mechanism 85

are carried by the coupling cross-tree c , and will, of course, rock or tilt with the cross-tree.

The tongue is free for pivotal motion on the cross-tree, and the finger-bar connects with the finger-bar bridge by pivots, which permit 90

the ordinary folding action of the finger-bar.

Hence with this construction the draft is applied entirely through the cross-tree c , the truck is dragged from the cross-tree and the cross-tree serves as a floating or knuckle joint 95

for permitting the necessary pivotal or rocking motion of the cutting mechanism. Hence, 100

as the cart or truck is dragged from the cross-tree, whenever extra hard cutting or an ob-105

struction is met with the tendency of the draft will be to lift the cross-tree and cutting mechanism and throw additional weight or traction onto the truck-wheels, which is the action desired to meet the increased work on the knife. 110

Moreover, inasmuch as the bearings for the knife-driving mechanism and the finger-bar bridge are both carried by the coupling cross-tree c , the crank-pin and the knife-head joints to the pitman will sustain a constant relation under all of the angular movements of the cutting mechanism. Plain pivots 115

may therefore be used to connect the crank-pin and the knife to the opposite ends of the pitman, and the friction on the knife from the driving mechanism is reduced to a 120

minimum, so far as torsional strain is concerned.

The bearings for the knife-driving mechanism and the finger-bar bridge have been 125

shown as formed integral with the cross-tree c . This is a good arrangement, because all of the said parts may be cast together as a single piece; but it must be obvious that the

action would be the same if the said bearings and the finger-bar bridge were made separate 130

from the cross-tree c and pinned fast thereto.

Again, it must be equally obvious that the cross-tree c , instead of being mounted for pivotal or rocking motion in the lugs b^2 of the frame, might be rendered rigid with the main 135

frame either by casting the same in one piece with the other sections of the main frame or

in any other way, and that the bearings for the knife-driving mechanism and the finger-bar bridge might be made separate from the cross-tree, but mounted thereon with freedom for rocking or pivotal motion. In other words, the said parts may take any suitable construction as long as the cross-tree *c* serves to couple the draft-tongue and the cutting mechanism to the forward end of the truck-frame with freedom for the independent pivotal motion of all of the said coupled parts. The action peculiar to this radical improvement has been thus described before noting the arrangement of levers for tilting the finger-bar, folding the finger-bar, and raising the knuckle-joint, because these levers may take any suitable arrangement best adapted for the purpose.

For tilting the finger-bar, I have shown a lever-casting *c*⁸ formed integral with the cross-tree *c*, to which casting *c*⁸ a hand-lever *c*⁹ is bolted, provided with the ordinary spring-pawl device *c*¹⁰, the pawl of which works over a notch-quadrant *g*⁵, forming a part of the tongue lug-casting *g*¹. This construction permits the cross-tree *c* and the cutting mechanism to be rocked at will and latched in any desired angular adjustment to the draft-tongue *g*. The finger-piece of the spring-pawl device is provided with a link *c*¹¹, which may be engaged over the top of the lever *c*⁹ to hold up the pawl and permit the cutting mechanism to float or move with freedom for oscillating motion in the cutting action.

For raising and lowering the knuckle-joint or cross-tree and for folding the finger-bar I have shown a hand-lever *h* as pivoted to the lower end of a notch-quadrant *h*¹ bolted to lug *h*² cast integral with the inner member of the frame-arms *b*¹. The said lever *h* is provided with the ordinary spring-pawl device *h*³ for engagement with the notches of the quadrant *h*¹, and the said quadrant is formed with limiting stops or lugs at its opposite ends and with a smooth and unnotched portion forward of its center, as best shown in Fig. 2.

To the lower end of the lever *h* is fixed a forwardly-projecting arm *h*⁴, which connects rearward of its forward end by a link *h*⁵ with a fixed arm *g*⁶ formed integral with the tongue lug-casting *g*¹. The forward extremity of the lever-arm *h*⁴ connects by a link *h*⁶ with the folding-lever *h*⁷, which is pivoted to the cross-tree, as shown at *h*⁷ in Fig. 4. The inner and lower end of the folding-lever *h*⁷ overreaches a cam-lug *f*⁸ on the inside shoe *f*⁹ for co-operation therewith to partially fold the finger-bar in the usual way. A thrust-rod *h*¹⁰ is shown as connecting the lifting-lever *h* with the foot-lever *h*¹¹, which is pivoted to a lug *h*¹², cast integral with the frame-piece *b*. With this arrangement of the lifting-lever and its connections it is obvious that the position of the draft-tongue relative to the forward end of the truck-frame may be varied at will through the parts *h*³, *h*⁴, and *g*⁶ for raising or lowering the coupling cross-tree *c* or knuckle-

joint into any desired position. For example, the same may be thrown from the position shown in Fig. 2 to the position shown in Fig. 5, and in this lifting action on the knuckle-joint the finger-bar will be folded upward from the position shown in Figs. 1, 2, and 3 to the position shown in Fig. 4. In other words, the ordinary amount of folding motion may be given to the finger-bar which is required for turning corners and lifting the same over stones, stumps, and other obstructions. The folding of the finger-bar is completed by hand in the usual way whenever it is desired to turn the same upward to its limit for transportation or travel on the road.

The seat-support *k* is shown as attached to a lug *k*¹ projecting rearward and upward from the frame-section *b*. The seat *k*² therefore brings the rider into such a position in respect to the frame that his weight will tend to counterbalance the forward end of the frame and the parts carried by the coupling cross-tree *c*. The foot-lever *h*⁹ and the connections therefrom enable the driver to utilize his weight, as well as the power from his hands, on the lifting-lever *h* for raising and lowering the knuckle-joint.

The lifting-levers and their connections could, of course, be arranged in any other suitable way. In practice it would probably be found more advantageous to bring the fulcrum of the lifting-lever *h* directly over the truck-axle.

When it is desired to have the cutting apparatus ride or float with its weight carried chiefly by the shoes, the lifting-lever *h* will be set so that the spring-pawl thereof will ride over the unnotched portion of the quadrant *h*¹.

It will of course be understood that minor details of the construction shown and described might be changed without departing from the spirit of my invention.

In respect to the coupling cross-tree *c* it should be further noted that the same always remains parallel with the truck-axle under the up and down movements thereof.

It has already been noted that extra hard cutting or an obstruction when met by the finger-bar will raise the knuckle-joint or cross-tree and throw increased weight onto the truck-wheels. This is directly contrary to the action, under like circumstances, on the old or standard construction. In the old or standard mower when the finger-bar meets an obstruction or the cutting becomes extra hard the shoes and supplemental frame become a fulcrum and lever upon which the tongue and the main frame attached to the truck-axle tend under the increased draft to lift the truck-wheels from the ground. With my improved construction the obstruction increases the traction by the increased weight thrown onto the truck-wheels when the knuckle-joint rises, and the shocks or jars from the obstruction are taken directly on the cross-tree and the pole without being transmitted to the truck-frame. Hence the truck-

frame may be made comparatively light. When extra hard cutting is struck, the increased draft required to operate the knife will cause a corresponding increase of traction on the truck-wheel.

From the foregoing statements it must be obvious that my invention constitutes a radical departure in front-cut mowing-machines, which has the effect of greatly improving the action, simplifying the construction, reducing the first cost, and adding to the durability of the machine.

It should be further noted that while the cross-tree *c* has been shown as continuous it would be possible to secure a floating and coupling joint with a cross-tree formed in discontinuous or separated sections. This would not give a construction which would be the full mechanical equivalent of the continuous cross-tree shown, but would be within the principle of my invention in broad point of view. The essential thing, broadly stated, is that the cross-tree or frame which carries the cutting apparatus shall wholly drag the truck instead of being propelled or partly propelled by the truck and that the floating, tilting, and folding features of the cutting apparatus shall be retained intact.

What I claim, and desire to secure by Letters Patent of the United States, is as follows:

1. In a front-cut mower, the combination with a truck, draft-tongue and cutting mechanism, of a single frame, pivoted to the truck-axle, and a cross-tree, coupling the tongue and cutting mechanism to the forward end of said frame, with freedom for independent pivotal movement of all of said coupled parts, whereby the cutting mechanism is free for tilting motion, the truck is dragged from said coupling cross-tree and the traction on the

truck-wheels will be increased when the cutting mechanism meets an obstruction or hard cutting, substantially as described.

2. In a front-cut mower, the combination with a truck and draft-tongue of a single frame pivoted to the truck-axle, a rocking cross-tree, pivotally connecting the draft-tongue to the forward end of said frame, bearings for the knife-driving mechanism and a finger-bar bridge fixed to said cross-tree, and a finger-bar pivoted to said bridge, all for cooperative action substantially as described.

3. In a front-cut mower, the combination with a truck, draft-tongue and cutting mechanism, of a single frame pivoted to the truck-axle, a cross-tree, coupling the tongue and cutting mechanism to the forward end of said frame, with freedom for the independent pivotal movement of all of said coupled parts, and means for latching the cutting mechanism to the tongue in any desired angular adjustment, substantially as described.

4. In a front-cut mower, the combination with a truck, draft-tongue and cutting mechanism, of a single frame pivoted to the truck-axle, a cross-tree coupling the tongue and cutting mechanism to the forward end of said frame, with freedom for the independent pivotal movement of all of said coupled parts, means for latching the cutting mechanism to the tongue, in any desired angular adjustment, and means for raising the coupled parts at their coupling or cross-tree knuckle-joint, substantially as described.

In testimony whereof I affix my signature in presence of two witnesses.

PLINY F. HODGES.
